UNITED STATES PATENT OFFICE.

EDWIN F. MURDOCK, OF WASHINGTON, DISTRICT OF COLUMBIA.

METHOD OF FORMING CONCRETE PAVEMENTS.

SPECIFICATION forming part of Letters Patent No. 423,796, dated March 18, 1890.

Application filed July 11, 1889; Serial No. 317,122. (No specimens.)

To all whom it may concern:

Be it known that I, EDWIN F. MURDOCK, a citizen of the United States, and a resident of Washington city, in the District of Columbia, 5 have invented new and useful Improvements in the Method of Forming Concrete Pavements, of which the following is a full and exact description, reference being had to the accompanying drawings.

10 This invention relates to improvements in the method of forming concrete pavements, and has for its objects to prevent the cracking, sliding, and rotting of the wearing-course.

To these ends the invention consists in forming in the course contiguous to the wearing-course indentations, into which the material of the wearing-course may flow when spread.

In the drawings, Figure 1 is a plan view of a street prepared with a hydraulic cement 20 concrete base provided with elongated grooves in two series. Fig. 2 is a sectional view of the same, showing in position the strips used in forming the grooves. Fig. 3 is a sectional view of the pavement complete.

25 In this class of pavements the thermal changes produce in the wearing-course an expansion and contraction. These actions cause in the pavements as at present constructed a movement of the wearing-surface on the base.

30 As the material forming the wearing-course is laid while hot, and therefore fully expanded, the contraction is quite considerable, and as the ductility of the material is small the pavement is pulled apart in cracks. This con-

35 tractile force operates along the diameters of the pavement from curb to curb and end to end. In thus operating along the length of the pavement the force generated is greater than that generated from curb to curb, and

40 when the pavement breaks it is across the length. If these cracks become numerous and the distance between any two of them is less than the distance between the curb, the crack takes place in a line with the length of

45 the pavement. Along the edges of these cracks the material disintegrates and rots, and in a short time forms a hole which has to be repaired at an additional cost.

It is to prevent the movement of the wearing-surface on the base that I provide the grooves A A and B B. The former extend across the street and the latter in the direc-

tion of the street. These grooves I form in the base as it is being laid by placing in the upper surface while it is soft strips of wood. 55 As the base is tamped down, the strips are driven down with it and left in the base while it is setting. When it has thoroughly set, the pieces may be taken out by placing the edge of a pick under the ends and raising them, or by any other suitable means. When they are thus taken out, the base is provided with a number of grooves in two series, the one extending across and the other lengthwise of the street. 60

In placing the strips the ends should lap, as shown in Fig. 1 of the drawings, in order to leave no continuous line unbroken in either direction. No particular care is necessary to be used in placing the strips. I place them 70 at about ten feet apart and in about the order shown in Fig. 1 of the drawings, though any other order will answer the purpose. In some instances I lay them obliquely across the street, especially at intersections, where the 75 strain is exerted in all directions; but as a general rule I prefer the design shown in the drawings. The strips may be of any desired thickness and length. That shown in the drawings is one inch thick and eight feet long. 80 After the strips are taken out of the base, as described, the wearing-course is spread upon it, flowing into the grooves A and B, as shown in Fig. 3. When thus spread, it is rolled hard, driving the material in the grooves solid. 85 When, now, the wearing-course commences to contract, the strain is resisted every ten feet by the sides of the grooves A and B, with which the said wearing-course is engaged. By thus taking up the strain at short intervals the multiplying of the force above referred to is prevented, and as the tensile strength of the wearing-course is greater than the contractile force generated at these intervals the breaking is obviated. 90

The series of grooves B, which are placed lengthwise of the street, are provided to prevent the rolling of the wearing-surface toward the gutter. This is caused by the softening of the wearing-course and in this condition sliding on the base down the grade of the street to the gutter. By preventing the sliding on the base, as is done by the grooves, this action is prevented, and the wearing-

course is maintained at its initial thickness throughout, thereby securing an evenly-wearing surface. It is obvious that I do not confine myself to the manner of placing these 5 grooves or of forming them, as either may be altered without changing the essential feature of the invention.

What I claim is—

1. The method of forming concrete pavements, which consists in laying a concrete base, forming elongated grooves therein extending across the lines of the contractile strains, and spreading upon the said base thus prepared a bituminous concrete wearing-course in a plastic condition adapted to flow into the said grooves, substantially as described.
2. The method of forming concrete pavements, which consists in laying a hydraulic concrete base, forming grooves and indentations therein while in a plastic condition, and

spreading upon the said base thus prepared a bituminous concrete wearing-course in a plastic condition adapted to flow into the said grooves and indentations, substantially as described. 25

3. The method of forming concrete pavements, which consists in laying a hydraulic concrete base, placing in the upper surface of the said base while in a plastic condition 30 strips of wood or other suitable material, extracting the said strips when the base has partly set to form grooves in the upper surface, and spreading on the base thus prepared a bituminous concrete wearing-course in a 35 plastic condition adapted to flow into the grooves thus formed, substantially as described.

EDWIN F. MURDOCK.
